UNITED STATES PATENT OFFICE.

JOHN S. FINCH, OF BRIDGEPORT, CONNECTICUT, ASSIGNOR TO THE SINGER MANUFACTURING COMPANY, A CORPORATION OF NEW JERSEY.

LOOP-TAKER-ACTUATING MECHANISM FOR SEWING-MACHINES.

1,232,263.

Specification of Letters Patent.

Patented July 3, 1917.

Application filed May 23, 1916. Serial No. 99,280.

To all whom it may concern:

Be it known that I, JOHN S. FINCH, citizen of the United States, residing at Bridgeport, in the county of Fairfield and State of Connecticut, have invented certain new and useful Improvements in Loop-Taker-Actuating Mechanism for Sewing-Machines, of which the following is a specification, reference being had therein to the accompanying drawings.

This invention relates to that class of sewing machines employing a needle-carrying bar having movements in different vertical planes and lateral movements of varying amplitude for effecting embroidery seams and designs comprising zigzag stitches, and has for its object to provide improved means for retarding and accelerating the movements of the loop-taker to meet the requirements of variations in the lateral movement of the needle.

In the accompanying drawings, which form a part of the specifications, Figure 1 is a sectional view in front side elevation of a sewing machine equipped with the present invention. Fig. 2 is an under side view of the sewing machine represented in Fig. 1. Fig. 3 is a view illustrating certain parts comprising the means for manually controlling the changes in amplitude of the lateral movements of the needle. Fig. 4 is a view, in perspective, of the front end portion of the loop-taker driving shaft and the gear member carried by the latter. Fig. 5 is a view in central section of the means employed for controlling the degree of lateral movement given the needle. Fig. 6 is a view, partly in full and partly in dotted lines, of certain of the elements shown in Fig. 5, later to be referred to.

Referring to the figures, 1 represents the bed-plate of the sewing machine upon which is mounted the bracket-arm comprising the arm bracket 2 and standard 3, 4 the main or needle-bar driving shaft provided at one end with the band-wheel 5 and at its opposite end with the shaft-flange 6 to which is pivotally connected the needle-bar actu-

ating link 7 connected with the needle-bar 8 carrying the needle 9 and 10 the cloth-presser suitably secured to the lower end of one form of commonly employed spring depressed cloth-presser carrying bar (not shown), the needle-bar 8 being mounted to move vertically in the needle-bar carrying frame 11 pivoted at its upper end on a stud-bolt 12 threaded into the arm-bracket 2.

13 represents the feed rock-shaft mounted in suitable bearings depending from the under side of the bed-plate and at its forward end operatively connected with the feed-dog carrying bracket 14 provided with the usual feed-dog 15, the opposite end of said shaft being connected by a crank-arm 16 with the feed connection 17, the upper end of the latter embracing the usual feed connection eccentric (not shown) carried by the main-shaft, thus transmitting from the latter feed movements to the feed-dog.

18 represents the feed lift rock-shaft mounted in the manner of shaft 13 and carrying at its forward end a crank-arm 19 provided with a stud-screw 20 carrying a slide-block 21 which engages the slot 22 formed in the end 23 of the bracket 14, the opposite end of said feed lift rock-shaft being connected by a crank-arm 24 with a feed lift connection 25 the upper end of which embraces a feed lift eccentric 26 carried by the main-shaft, thus transmitting from the latter vertical movements to the feed-dog.

27 represents a spiral gear carried by the main-shaft and meshing with a like gear 28 carried by the cam-shaft 29 mounted at one end in a bearing 30 formed in the arm-bracket, and at its opposite end in a suitable bearing formed in an arm-bracket plate (not shown) common to the present construction. The gears 27 and 28 are of the ratio of two to one, thus giving to the cam-shaft one rotation to two rotations of said main-shaft and on the cam-shaft is mounted a needle vibrating cam 31, later to be referred to.

32 represents an oscillating cam shaft

mounted in a bearing 32' formed in the arm-bracket and carrying on its outer end a crank-arm 33 connected by a link 34 with the end of a rock-lever 35, the opposite end of which is connected with a rod 36 which partakes of vertical movements, at the will of the operator through a suitable knee-lever or treadle (not shown) and in opposition to the resiliency of the spring 37, the latter normally acting to hold the end 38 of the crank-arm 33 in contact with the stationary lug 39 forming part of the collar 40 secured on the hub 41 of the oscillating shaft bearing, or in position to hold 15 the needle-bar against lateral movements.

The inner end of the shaft 32 is provided with a groove 42 in which tracks a slide-block 43 mounted on the inner end of a stud 44 which passes through the needle-carrying frame connection 45 and through a shifting lever connection 46 and secured by a nut 47 and flange 48 against movement in the direction of its length, the connection 45 being forked to embrace the cam 25 31 and at its opposite end pivotally connected to the needle-bar carrying frame 11.

49 represents a loop-taker actuating shaft mounted in suitable bearings depending from the sewing machine bed-plate and at its forward end carrying a sliding sleeve 50, held against lengthwise movement by the flange 51 and suitably secured collar 52, having a spiral groove 53 and a spiral gear member 54, said shaft being provided with a 30 suitably secured spiral groove follower 55 which, in practice, tracks the groove 53, said gear member meshing with a like gear 56 secured on the loop-taker shaft 57, the latter being mounted in the usual manner below 35 said bed-plate and carrying a loop-taker 58. Upon the rear end of the shaft 49 is secured a belt driven pulley 59 connected by a belt 60 with a driving pulley 61 carried by the main-shaft, said belt driving and driven 40 pulleys being of the ratio of two to one, thus giving to the loop-taker shaft two rotations to one of said main-shaft.

62 represents a sleeve loosely mounted on the shaft 49 and held against lengthwise movement on said shaft by suitably secured collars 63 and 64, said sleeve having formed integral with it a bearing hub 65 upon which is pivoted one end of the loop-taker actuating shaft link 66, the opposite end of 55 said link being pivotally attached to the lower end of the loop-taker actuating shaft shifting lever 67 mounted to oscillate on a bearing stud 68 secured in the standard 3 and pivotally connected at its upper end 60 with the shifting lever connection 46 whose opposite end is pivoted onto the stud 44.

From the foregoing it will be readily understood that provision is made for actuating the needle either in a given path, as

when effecting the ordinary straightaway 65 seam, or in different paths, as when effecting the so-termed zigzag seam, and that when effecting the latter seam the loop-taker actuating shaft will be given movements in the direction of its length from the cam 31 70 through the connection 45, 46, 67, 66 and 62, thus causing the follower 55 to act on the groove 53 to, through the gear member 54, accelerate or retard the movements of the gear member 56 fast on the loop-taker shaft 75 57, dependent upon the direction of the lengthwise movements of the shaft 49.

Having thus set forth the nature of the invention, what I claim herein is:—

1. In a sewing machine, the combination 80 with a fabric feeding and stitch-forming mechanism including a needle having stitch-forming movements in different paths, a main-shaft from which said needle is actuated, a loop-taker shaft provided with a 85 loop-taker and a gear member, and a loop-taker actuating shaft operatively connected at one end with said main-shaft and at its opposite end provided with means, including a loosely mounted sleeve provided with 90 a gear member meshing with the gear member carried by said loop-taker shaft, for accelerating and retarding the movements of said loop-taker to maintain a proper timing 95 of the latter with respect to the movements of said needle.

2. In a sewing machine, the combination with a fabric feeding and stitch-forming mechanism including a needle having stitch-forming movements in different paths, a 100 main-shaft from which said needle is actuated, a loop-taker shaft provided with a loop-taker and a gear member, and an end-wise movable loop-taker actuating shaft provided with a follower and operatively connected at one end with said main-shaft and at its opposite end carrying a loosely mounted sleeve provided with a gear member meshing with the gear member carried by 105 said loop-taker shaft and having an internal spiral groove co-operating with said follower to accelerate and retard, through the end-wise movements of said loop-taker actuating shaft, the movements of said loop-taker to maintain a proper timing of the latter with 110 respect to the movements of said needle.

3. In a sewing machine, the combination with a fabric feeding and stitch-forming mechanism including a needle having stitch-forming movement in different paths, a 120 main-shaft from which said needle is actuated, a loop-taker shaft provided with a loop-taker and a gear member, and a loop-taker actuating shaft provided with a follower and operatively connected at one end with said main-shaft and at its opposite end carrying a loosely mounted sleeve provided with a gear member meshing with the gear 125

member carried by said loop-taker shaft and having an internal spiral groove coöperating with said follower to accelerate and retard the movements of said loop-taker to maintain a proper timing of the latter with respect to the movement of said needle.

5 In testimony whereof, I have signed my

name to this specification, in the presence of two subscribing witnesses.

JOHN S. FINCH.
